UNITED STATES PATENT OFFICE.

JONAS NORTHROP, OF HOPEDALE, MASSACHUSETTS, ASSIGNOR TO HOPEDALE MANUFACTURING COMPANY, OF MILFORD, MASSACHUSETTS, A CORPORATION OF MASSACHUSETTS.

TAKE-UP MECHANISM FOR LOOMS.

Application filed January 29, 1923. Serial No. 615,516.

To all whom it may concern:

Be it known that I, JONAS NORTHROP, a citizen of the United States, residing at Hopedale, in the county of Worcester and State of Massachusetts, have invented certain new and useful Improvements in Take-Up Mechanisms for Looms; and I do hereby declare the following to be a full, clear, and exact description of the invention, such as will enable others skilled in the art to which it appertains to make and use the same.

The present invention relates to looms and more particularly to take-up mechanisms for looms.

The usual types of looms include a take-up mechanism together with a let-back mechanism which is adapted to let the cloth back a certain number of picks after detection of absence of filling. Prior types of let-back mechanisms usually employed a ratchet or pawl device maintained in constant engagement with a toothed wheel and adapted to let back the cloth in accordance with the adjustment of the ratchet or pawl. This let-back of the cloth took place merely because of the tension upon the cloth. It will be appreciated that this mechanism is open to the objection that its action is not positive and that the engagement of the ratchet device with the toothed wheel imposes a constant and detrimental wear upon the apparatus. The object of the present invention is to provide a loom having a let-back mechanism which will positively control the movement of the cloth after absence of filling. Another object of the invention is to provide a loom in which the let-back is normally maintained out of engagement with the take-up mechanism and in which the let-back acts positively to move the cloth a predetermined distance. With these and other objects in view, the present invention consists of the loom hereinafter described and particularly defined in the claims.

In the accompanying drawings Fig. 1 is an elevation of a portion of a loom showing the improved take-up and let-back mechanisms in normal operating condition; Fig. 2 is an elevation of the apparatus shown in Fig. 1 after detection of the filling absence; Fig. 3 is a rear elevation of the let-back mechanism; Fig. 4 is a plan view of the mechanism shown in Fig. 3; Fig. 5 is an elevation of the apparatus shown in Fig. 3; and Fig. 6 is a detail showing the connec-

tion between the worm engaging mechanism and the let-back mechanism.

The illustrated embodiment of the invention is described as follows: The cloth 10 is wound upon a wind-up roll 12 yieldingly maintained against a draw roll 13 so as to be frictionally driven thereby. The draw roll itself is positively rotated by means of the gear train 14, 16, 18 and 20. The gear 20 is known as the change gear and is adjustably mounted in a slotted bracket 22. The number of teeth in the gear 20 bears a fixed relation to the grade of cloth, and the size of the gear used will depend upon the number of picks of the weft per inch in the woven fabric. The gear 20 meshes with a worm 24 mounted upon a shaft 26 which is rotated by any suitable gearing connected with the cam shaft. Under normal running conditions, the gear 20 rotates in a clockwise direction.

The worm 24 is adapted to be moved into and out of engagement with the gear 20 through the action of a sliding bracket 28 which is provided with a bearing 30 in which shaft 26 is journaled. The bracket 28 is provided with slots 32 and 34 in which are received studs 36 and 38 secured to any suitable stationary part of the loom. The stud 38 has mounted thereon a cam 40 which is connected with a cam arm 42 and which is adapted to bear against an upper cam lug 44 and a lower cam lug 46 attached to the bracket 28. It will be seen that upon moving the cam arm 42, the cam will bear against the lugs and raise or lower the bracket at the same time carrying the worm 24 into or out of engagement with the gear 20. The cam is preferably provided with bearing surfaces of such form as to engage the lugs 44 and 46 and lock the bracket in either position.

The oscillations of the cam 40 are controlled by the movement of the weft hammer 48 and the detector slide 50 when the filling is absent. The weft hammer is oscillated in the usual manner deriving its motion from a weft hammer lever of the usual type (not shown). On its forward motion, the slide 50 engages a lever 52 which actuates the change lever 54 which is in turn connected with the cam arm 42 by a link 56, this latter link being pivoted to the cam arm by a stud 58. This motion rotates the cam in a counter-clockwise direction and

lowers the worm from engagement with the gear 20. The foregoing details of construction are substantially as described in Northrop Patent No. 1,479,154.

- 5 The let-back mechanism includes an engagement dog 60 mounted upon a stud 62 which is adjustably secured in the slot 64 of a bracket 66 secured to the frame of the loom. The dog is provided with a handle 68. 10 A segmental gear member 70 is pivoted at 72 upon the upper surface of the dog and is provided with an integral stop member 74 adapted to hold the gear upon the dog in the manner shown in Fig. 5. When the 15 dog is in the position shown in Fig. 5, the gear teeth are preferably disposed along a circular arc concentric with the stud 62. The motion of the dog is limited by an adjustable screw member 76 which is adapted 20 to strike a surface 78 of the bracket 66. The dog is yieldingly connected with the cam arm 42 through a link 80 connected at one end on a stud 82 of the dog and received at the other end in the threaded collar 84 upon 25 which is wound a helical spring 86 secured at its other end to the stud 58. The link 80 is bent in a manner to provide a passage or slot 81 in which the stud 82 is received. The tension of the spring 86 may be adjusted 30 by varying the relative positions of the link 80 and the collar 84. The spring is preferably so adjusted that when the parts are in the position indicated in Fig. 1, no tension is upon the spring, but upon the movement 35 of the arm 42, the spring will immediately be put under tension and draw the dog so that the segmental gear engages with the change gear 20.

It will be seen that upon the forward motion of the slide 50, the parts will assume the positions as shown in Fig. 2, the cam being actuated to lower the bracket 28 and disengage the worm from the gear 20, the dog being at the same time moved into engagement with the gear 20, the amount of the movement depending upon the adjustment of the screw 76. The various parts are so relatively disposed that the segmental gear 70 comes into engagement with gear 20 before the worm 24 drops out of engagement, otherwise the tension on the cloth would rotate the gear 20 too far in a counter-clockwise direction. The flexible connection between the dog and the arm 42 allows this 55 action to take place without shock or danger of breaking any of the gear teeth. Upon engagement of the gear 70 with the change gear 20, the cloth is positively let back a certain definite amount, depending upon the

motion of the dog before the screw 76 strikes 60 the surface 78 of the bracket. Upon motion of the lever 54 to the position shown in Fig. 1, the worm is again brought into engagement with the change gear and upon continued rotation of the worm, the change 65 gear is rotated in a clockwise direction, thereby throwing off the dog 60 into the position shown in Fig. 1. Due to the provision of the slot 81 in the link 80, the dog 70 itself is not thrown off by the return motion of the arm 42, because if such were the case, the dog might be thrown out of engagement before re-engagement of the worm with the gear, thereby taking the gear out of positive control. 75

Provision is made for allowing the operative to rotate the wind-up mechanism by hand if desired. To this end, the dog is provided with a member 88 having a slot 90 by which the member 88 may be adjustably secured to the dog through a bolt 92, as indicated in Fig. 3. The member 88 is provided at its lower end with a bunter 94 adapted to strike the lower end of the lever 54 when the handle 68 is pulled outwardly. 85 When this is done, it will be seen that the worm 24 is dropped out of engagement with the gear, while at the same time the segmental gear 70 is also maintained out of engagement with the change gear. The operative may then take up or let back the cloth 90 by hand in any desired manner but it is preferred to use a hand wheel construction of the type described in the Northrop Patent No. 1,446,655. 95

The advantages of the improved take-up mechanism of the present invention are (1) that the wear ordinarily attendant upon the constant engagement of the let-back mechanism is eliminated; (2) that the cloth is 100 positively moved a predetermined distance by the action of the let-back; and (3) provision is made for a convenient winding of the cloth by hand whenever the operative so desires. 105

I claim:

A loom having, in combination, a take-up mechanism, means for driving the take-up mechanism, a change lever, connections between the change lever and the driving 110 means to disengage the driving means from the take-up mechanism, a let-back device normally maintained out of engagement with the take-up mechanism, and a bunter mounted upon the let-back device and adapted 115 to move the change lever upon manual movement of the let-back device.

JONAS NORTHRUP.
